SLIPPER SOLE

Joseph P. Famolare, Jr., Florence, Italy, assignor to
Famolare, Inc., New York, N.Y.

Filed Aug. 22, 1974, Ser. No. 499,495

Term of patent 14 years

Int. Cl. D2—04

U.S. Cl. D2—320

Fig. 1

Fig. 2

Fig. 3

Fig. 4

Fig. 5

Fig. 6

FIG. 1 is a front and side perspective view of a slipper sole showing my new design;

FIG. 2 is a side elevational view thereof;

FIG. 3 is a front elevational view thereof;

FIG. 4 is a top plan view thereof;

FIG. 5 is a side elevational view showing the opposite side of that shown in FIG. 2;

FIG. 6 is a rear elevational view; and

FIG. 7 is a bottom plan view.

I claim:

The ornamental design for a slipper sole, substantially as shown and described.
